EVACUATING MACHINE

George H. Busch, St. Louis, Mo.

Application December 28, 1936, Serial No. 118,009

8 Claims. (Cl. 226—116)

The invention relates to an evacuating machine and more especially to a vacuum pump to be used in filling liquids into bottles or containers without overflow and also to evacuate electric light bulbs, radio vacuum tubes, neon tubes, etc.

The primary object of the invention is the provision of a machine of this character, wherein through the use of an evacuating tube the air within a container, bottle or the like may be readily evacuated so that in the filling of the container, bottle or the like with liquid the said liquid can be dispensed therein without the possibility of overflow and thus eliminating waste of the liquid.

Another object of the invention is the provision of a machine of this character, wherein a movable carriage has fitted therewith presser rollers which are adapted to compress a rubber evacuating tube on the travel of the carriage for evacuating purposes to remove air from containers, bottles or the like, the machine in its entirety being of novel construction and the carriage is movably supported in a unique manner and with the result that the rollers in the rotation thereof will not exert a pull upon the evacuating tube during movement of said carriage.

A further object of the invention is the provision of a machine of this character, which is simple in its construction, reliable and effective in operation, readily and easily handled for evacuating purposes, strong, durable, and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is a side elevation of the machine constructed in accordance with the invention showing by full lines a portion of a liquid vat and by dotted lines a bottle to be filled in association therewith.

Figure 2 is a fragmentary sectional view on the line 2—2 of Figure 1 looking in the direction of the arrows.

Figure 3 is a sectional view on the line 3—3 of Figure 1 looking in the direction of the arrows.

Figure 4 is a fragmentary sectional view on the line 4—4 of Figure 3 looking in the direction of the arrows.

Figure 5 is a vertical longitudinal sectional

view through the filling and evacuating head of the machine.

Figure 6 is a sectional view on the line 6—6 of Figure 1 looking in the direction of the arrows.

Similar reference characters indicate corresponding parts throughout the several views in the drawings.

Referring to the drawings in detail, the machine comprises a base 10 on which is carried a stand including a substantially rectangular 10 shaped supporting frame 11 having therein spaced parallel longitudinally directed guide rods 12 constituting tracks. Movably supported upon the tracks constituted by the rods 12 is a carriage.

The carriage comprises a chassis 13 supporting track rollers 14 which travel upon the tracks within the frame 11. Rising from the chassis 13 of the carriage is an upstanding vertical rack 15 having journaled therein upper and lower presser rollers 16 and 17, respectively, the axle 18 for the lower roller being fixedly journaled in the said rack 15 and secured to one end of said axle is a rack gear 19 meshing with a stationary toothed rack 20 superposed horizontally above the frame 11 and supported by posts or uprights 21 which at their lower ends are suitably fixed to the said frame. The axle 22 of the upper roller 16 is vertically adjustable in slots 23 provided in the side members of the rack 15, there being adjustable cleats 24 carried by these side members to limit the upward movement of the said axle 22 for the upper roller 16.

Trained between the rollers is an evacuating relatively thick walled rubber tube 25 which is adapted to be compressed by the said rollers 16 and 17 when the carriage is moved on the tracks and thus affording a suction medium. The tube 25 is held in supports 26 extended upwardly from the frame 11 and fixed thereto in any suitable manner, these supports being adapted to hold the said tube relatively taut and are located next to opposite ends thereof.

At one end of the frame 11 is a bracket 27 carrying a depending cylindrical filling and evacuating head 28 having interiorly thereof a suction chamber 29 from which leads an outlet suction nipple 30 having connection by an elbow 31 with the tube 25 at one end thereof, the other end of the tube being open to the atmosphere. Leading into the head 28 is a feed nipple 32 to which is connected a filling tube 33 adapted to be lowered into a liquid vat 34 to extend into the liquid below the level thereof within the vat and this end of the said tube is fitted with a re-

turn check valve 35. Depending into the chamber 29 is a filling nozzle 36 which fits the filling passage 37 from the nipple 32 to the said nozzle 36. The chamber 29 in the head 28 opens centrally through the bottom end of the said head and suitably fitting this open end of the chamber is a centering sleeve 38 to be accommodated within the open mouth of a bottle 39 to be filled while concentrically about the said sleeve 38 is 5 a sponge rubber sealing cap or gasket 40 which seals the mouth of the bottle 39 when the same is pressed against said cap or gasket on the slight protruding of the sleeve 38 and nozzle 36 within said bottle mouth.

10 One of the rods 12 has adjustably fitted thereon a stop 41 which limits the movement of the carriage in one direction upon the tracks.

When it is desired to fill the bottle 39 with liquid within the vat 34, the bottle is pressed 20 against the cap or gasket 40 with the spout 36 slightly protruding into the mouth of said bottle and the sleeve 38 fitting within said mouth for the centering of the bottle when the carriage, which is normally close to the end of the tube 25 next to the bracket 27, is moved, motion being 25 imported thereto by the attachment of a hand crank or other power medium (not shown) to the end 42 of the axle 18 and thus the tube 25 will become compressed causing a suction interiorly 30 thereof and in this fashion air will be evacuated from within the bottle 39 and the liquid from the vat 34 will be drawn into said bottle. The extent 35 of movement of the carriage regulates the quantity of liquid to be drawn into the bottle 39 and thus by setting the stop 41 the said carriage can be stopped at a determined locality and in this fashion avoiding any possibility of over-filling of the bottle or overflow from the same.

It is, of course, understood that the carriage 40 may be moved either manually or through mechanical means, this being optional.

When the tube 25 is compressed under the action of the rollers 16 and 17, a suction is set up 45 in the tube so that the latter operates as an evacuating medium for evacuation within the bottle or the like 39 when the same is placed in position to be filled through the head 28 of the machine.

The carriage after evacuation operation is 50 returned to normal position next to its end adjacent to the head 28 of the machine. On the unsealing of the bottle or the like 39 from the head 28 of the machine, the vacuum is broken and by 55 the gear 19 meshing with the rack 20 there will be no pulling upon the tube 25 when the carriage is in motion.

What is claimed is:

1. A machine of the character described comprising a stand, a carriage movably fitted in said stand, presser rollers arranged in the carriage, a rack gear rotatable with one of the presser rollers, a stationary rack in the stand and meshing with said rack gear, a compressible tube supported within the stand and trained between the 60 rollers to be compressed thereby for effecting a suction interiorly of said tube, and a head supported by the stand and having independent filling and 65 suction passages, the suction passage being in communication with the compressible tube, a supply conduit leading to the filling passage in 70 said head, with said rack gear, a compressible tube supported within the stand and trained between the rollers to be compressed thereby for effecting a suction interiorly of said tube, a head supported by the stand and having independent filling and suction passages, the suction passage being in communication with the compressible tube, and a supply conduit leading to the filling passage in 75 said head.

2. A machine of the character described comprising a stand, a carriage movably fitted in said stand, presser rollers arranged in the carriage, a rack gear rotatable with one of the presser rollers, a stationary rack in the stand and meshing

with said rack gear, a compressible tube supported within the stand and trained between the rollers to be compressed thereby for effecting a suction interiorly of said tube, a head supported by the stand and having independent filling and 5 suction passages, the suction passage being in communication with the compressible tube, and a supply conduit leading to the filling passage in 10 said head.

3. A machine of the character described comprising a stand, a carriage movably fitted in said stand, presser rollers arranged in the carriage, a rack gear rotatable with one of the presser rollers, a stationary rack in the stand and meshing with said rack gear, a compressible tube supported within the stand and trained between the rollers to be compressed thereby for effecting a suction interiorly of said tube, a head supported by the stand and having independent filling and 15 suction passages, the suction passage being in 20 communication with the compressible tube, a supply conduit leading to the filling passage in 25 said head, and means adjustably arranged in the stand for limiting the movement of the carriage in one direction.

4. A machine of the character described comprising a stand, a carriage movably fitted in said stand, presser rollers arranged in the carriage, a rack gear rotatable with one of the presser rollers, a stationary rack in the stand and meshing with said rack gear, a compressible tube supported within the stand and trained between the rollers to be compressed thereby for effecting a suction interiorly of said tube, a head supported by the stand and having independent filling and 30 suction passages, the suction passage being in communication with the compressible tube, a supply conduit leading to the filling passage in 35 said head, and means adjustably arranged in the stand for limiting the movement of the carriage 40 in one direction, and a check return valve associated with said conduit.

5. A machine of the character described comprising a stand, a carriage movably fitted in said stand, presser rollers arranged in the carriage, a 45 rack gear rotatable with one of the presser rollers, a stationary rack in the stand and meshing with said rack gear, a compressible tube supported within the stand and trained between the rollers to be compressed thereby for effecting a 50 suction interiorly of said tube, a head supported by the stand and having independent filling and suction passages, the suction passage being in communication with the compressible tube, a supply conduit leading to the filling passage in 55 said head, means adjustably arranged in the stand for limiting the movement of the carriage in one direction, a check return valve associated with said conduit, and a sealing cap on the head for the sealing of a container when engaged 60 therewith and in communication with the suction and filling passages of said head.

6. A machine of the character described comprising a stand, a carriage movably fitted in said stand, upper and lower presser rollers arranged 65 in the carriage, the upper roller being adjustable, a rack gear rotatable with one of the presser rollers, a stationary rack in the stand and meshing with said rack gear, a compressible tube supported within the stand and trained between the 70 rollers to be compressed thereby for effecting a suction interiorly of said tube, a head supported by the stand and having independent filling and suction passages, the suction passage being in 75 communication with the compressible tube, a

supply conduit leading to the filling passage in said head, means adjustably arranged in the stand for limiting the movement of the carriage in one direction, a check return valve associated with said conduit, a sealing cap on the head for the sealing of a container when engaged therewith and in communication with the suction and filling passages of said head, and means for limiting the adjustment of the uppermost presser roller relative to the lowermost presser roller.

7. A machine of the character described comprising a stand, a carriage movably fitted in said stand, upper and lower presser rollers arranged in the carriage, the upper roller being adjustable, a rack gear rotatable with one of the presser rollers, a stationary rack in the stand and meshing with said rack gear, a compressible tube supported within the stand and trained between the rollers to be compressed thereby for effecting a suction interiorly of said tube, a head supported by the stand and having independent filling and suction passages, the suction passage being in communication with the compressible tube, a supply conduit leading to the filling passage in said head, means adjustably arranged in the stand for limiting the movement of the carriage in one direction, a check return valve associated with said conduit, a sealing cap on the head for the sealing of a container when engaged therewith and in communication with the suction and filling passages of said head, means for limiting

the adjustment of the uppermost presser roller relative to the lowermost presser roller, and a rack on the carriage and having the presser rollers supported therein.

8. A machine of the character described comprising a stand, a carriage movably fitted in said stand, upper and lower presser rollers arranged in the carriage, the upper roller being adjustable, a rack gear rotatable with one of the presser rollers, a stationary rack in the stand and meshing with said rack gear, a compressible tube supported within the stand and trained between the rollers to be compressed thereby for effecting a suction interiorly of said tube, a head supported by the stand and having independent filling and suction passages, the suction passage being in communication with the compressible tube, a supply conduit leading to the filling passage in said head, means adjustably arranged in the stand for limiting the movement of the carriage in one direction, a check return valve associated with said conduit, a sealing cap on the head for the sealing of a container when engaged therewith and in communication with the suction and filling passages of said head, means for limiting the adjustment of the uppermost presser roller relative to the lowermost presser roller, a rack on the carriage and having the presser rollers supported therein, and a support for the head and carried by the stand.

GEORGE H. BUSCH.
